UNITED STATES PATENT OFFICE

SAMUEL OSTERMAN, OF BRONX, NEW YORK

LAMP SOCKET

Application filed April 20, 1929. Serial No. 356,823.

My invention relates to lamp sockets and a method of preparing the same.

More particularly stated I seek to improve lamp sockets of the kind used for holding 5 incandescent lamps, my purpose being to fix the sheet metal screw shell of the socket more firmly in position, and to center it accurately.

In this connection it may be noted that a lamp socket of the general type here contemplated 10 comprises a cup-like socket made of insulating material, and a metallic screw shell housed within said socket; and that difficulty has heretofore been experienced in centering the metallic screw shell relatively to 15 the socket, and in holding said screw shell firmly in place within the socket.

By my invention I seek not only to center the screw shell within the socket but also to give it a firm anchorage therein.

20 I also seek to improve the structure of the lamp socket, for the purpose of increasing the efficiency thereof.

Reference is made to the drawing forming a part of this specification, and in which like 25 reference characters indicate like parts throughout the several figures.

Figure 1 is a substantially central vertical section through my improved lamp socket, and is taken upon the line 1—1 of Figure 3, 30 looking in the direction indicated by the arrows.

Figure 2 is a substantially central vertical section through the lamp socket, before its completion, and shows a plunger and a forming die as used in the manufacture of the lamp 35 socket.

Figure 3 is a plan view of the lamp socket shown in Figure 1.

40 Figure 4 is a side elevation of the sheet metal screw shell.

Figure 5 is an end elevation of the plunger used for securing in position the sheet metal screw shell.

45 The body portion of my improved lamp socket is shown at 6, and is made of insulating material, preferably of a kind which can be softened by the gentle application of heat. There are any number of such insulating materials in general use, among them being va-

rious compositions commonly known as rubber compositions.

The socket 6 is provided with an opening 7 and with a bottom 8 bounding this opening, the socket being thus substantially cup-shaped.

The socket is provided internally with a number of grooves 9, 9, 9, 9, disposed substantially parallel with each other and with the general longitudinal axis of the shell.

60 Located within the socket 6 is a lining 10, made of sheet metal and corrugated spirally as shown, being thereby threaded.

The screw shell 10 is provided with a single slot 11 extending longitudinally of its axis. 65 This enables the screw shell to be compressed slightly, and thus readily sprung into the socket 6.

The screw shell 10 is provided with spacing leaves 12, in this instance four in number. 70 The screw shell is further provided with two smaller spacing leaves 13, 13, located upon opposite sides of the slot 11.

The screw shell 10 is provided with a number of anchor points 14, equal to the number 75 of the grooves 9. In the particular instance here shown there are four anchor points 14, and four grooves 9.

Wires 15 and 16 are used in connection with the screw shell 10. The wire 15 leads to the inner contact button 17, and the wire 16 is connected at the point 18 with the body portion of the screw shell 10.

The socket 6 is provided with holes 19 and 20, through which these wires are threaded.

85 Referring to Figure 2 a forming die appears at 21, and has the proximate form of a massive cup, provided with holes 22 and 23.

The socket 6 fits detachably into the forming die 21, the wires 15 and 16 extending 90 downwardly through the holes 22 and 23.

A plunger, co-acting with the forming die 21 and movable relatively thereto, is shown at 24. The plunger is provided with a smooth cylindrical portion 25, and with an annular flange 26.

95 The flange 26 carries a number of presser fingers 27, equal to the number of grooves 9 of the socket 6, or to the number of anchor points 14 of the screw shell 10. In the par-

ticular instance here illustrated there are four of these presser fingers 27.

Housed within the plunger 24, and partially encircled by the annular flange 26, is a heating coil 28. The purpose of this heating coil is to heat the plunger, and particularly the annular flange 26 thereof.

In assembling the lamp socket, the screw shell 10 of sheet metal is compressed slightly, so that the slot 11 is narrowed a little, and the screw shell is thereupon placed within the socket 6, the wires 15, 16 being brought out through the holes 19 and 20.

In doing this, the anchor points 14 spring radially outward, so as to press against the bottoms of the grooves 9.

Next the lamp socket, as yet unfinished, is placed within the forming die 21, as indicated in Figure 2, and the plunger 24 is brought down. The heating coil 28 keeps the plunger hot, and because of this fact the screw shell 10 is also heated. This is particularly the case with the upper portion of the screw shell, including the annular flange 26.

25 The anchor points 14, being heated and also pressed downwardly and outwardly by the presser fingers 27, are forced radially outward and driven slightly into the socket 6, as may be understood from Figures 1 and 2.

30 Thus the screw shell 10 is anchored firmly within the socket 6. Each anchor point 29 now acts as a barb, and the anchor points thus prevent any retrograde movement of the screw shell 10, and hold the same firmly within 35 in the socket 6.

Figure 2 shows the anchor points 14 as simply resting against the adjacent bottoms of the grooves 9, and ready to be thrust into the wall of the socket. When the plunger descends a trifle, the anchor points 14 are partially embedded within the material of the socket, as indicated in Figure 1. Next the plunger is withdrawn, and the lamp socket, now finished, is removed from the forming die.

I do not limit myself to the precise apparatus and method here illustrated and described, as variations therein may be made without departing from my invention, the 50 scope of invention being commensurate with my claims.

Having thus described my invention, what I claim as new and desire to secure by Letters Patent is as follows:

55 1. A lamp socket, comprising a hollow cup-like member of insulating material adapted to be softened by heat, said cup-like member being provided internally with grooves, and a screw shell located within said cup-like member and provided with anchor points extending into said grooves, said screw shell being further provided with a slot for enabling said screw shell to be sprung into said cup-like member.

65 2. The method herein described of prepar-

ing a lamp socket; which consists in providing a hollow socket of material adapted to be softened by heat, placing within said socket a metallic screw shell provided with anchor points, and applying heat and pressure to said screw shell in order to force said anchor points into the substance of said socket.

70 3. The combination of a hollow socket made of insulating material and provided internally with grooves, and a screw shell made of sheet metal and located within said socket, said screw shell being provided with anchor points extending into said grooves and thence into the substance of said shell so as to serve as barbs.

75 4. A lamp socket, comprising a socket of insulating material and a metallic screw shell disposed within said socket and threaded internally, said screw shell being provided with anchor points having portions forced into the substance of said socket and serving as barbs for holding said screw shell in place within said socket.

80 5. A lamp socket, comprising a substantially cup-shaped socket of insulating material and a threaded shell made of sheet metal and located within said socket, said shell having anchor points forced into the substance of said socket and serving as barbs to hold said screw shell within said shell.

85 6. A lamp socket, comprising a substantially cup-shaped socket of insulating material and a threaded shell made of sheet metal and located within said socket, said shell being provided with portions forced outwardly into the substance of said shell, and serving as barbs.

90 Signed at New York city, in the county of New York and State of New York, this 8th day of April, 1929.

105 SAMUEL OSTERMAN.
